PREFABRICATED GARMENT CONSTRUCTION

Bernard Pundyk, Sunnyside, and Fred Meer,
New York, N.Y.

Application January 17, 1956, Serial No. 559,700

1 Claim. (Cl. 2—243)

This invention relates to new and useful improvements and structural refinements in garment construction, and in particular the invention concerns itself with the construction of garments from prefabricated components.

In the practice of so-called home sewing, the housewife has been confronted with the necessity of first purchasing a paper pattern, pinning sections of the pattern to the material from which the garment was to be made, cutting out pieces of the material in accordance with the pattern sections pinned thereto, basting the cut out material pieces and finally sewing the same together into a complete garment. This procedure was not only time consuming, but it was also quite difficult, particularly for a novice. As a result, many housewives were inclined to purchase a ready-made garment in preference to spending time, effort and money in trying to make one themselves. Moreover, even those who attempted to do their own work often found that their product was ill-fitting or otherwise lacking the characteristics of the ready-made variety.

The present invention eliminates the foregoing disadvantages first by altogether dispensing with the conventional paper pattern and providing pre-shaped or pre-cut sections of material ready for assembly, and second, by marking the pre-shaped garment sections with seam indicating lines and other orienting indicia, whereby they may be quickly, easily and accurately assembled even by persons of very limited skill.

As such, the invention also contemplates furnishing all the needed components such as the pre-shaped garment sections, thread, buttons, etc., for a single garment in an individual package, appropriately marked with the size, color and nature of the garment, so that the same may be quickly and easily selected and purchased by the prospective user with the knowledge that all the required material for the project is at hand.

With the foregoing more important objects and features in view, and such other objects and features as may become apparent as this specification proceeds, the invention resides in the arrangement of parts and details of construction substantially as shown in the accompanying drawing, wherein like characters of reference are employed to designate like parts and wherein for illustrative purposes:

Figure 1 is a group plan view showing a plurality of individual, pre-shaped garment sections marked with seam indicating lines and other indicia for sewing the same together;

Figure 2 is a fragmentary perspective view illustrating a clip used for temporarily holding together a pair of superposed garment sections;

Figure 3 is a fragmentary plan view showing a plurality of garment sections embodied in a unitary sheet of material having lines of perforations for separating the sections therefrom by tearing; and

Figure 4 is a fragmentary perspective view, on an enlarged scale, of the sheet of material shown in Figure 3.

Referring now to the accompanying drawing in detail,

2

particularly to Figure 1 thereof, the reference characters A, B, C, D and E designate a plurality of individual garment sections or pieces of material from which the garment is to be made, these sections being pre-cut or pre-shaped in accordance with the size and shape of the respective portions of the garment which they constitute. For purposes of simplicity of illustration, the sections A, B, etc. have been shaped arbitrarily, it being understood, of course, that the teachings of the invention may be applied to the construction of garments of various different types.

As illustrated in the drawing, the garment sections D, C, B and E have marginal edges 10, 11, 12 and 13, respectively, which are to be joined to matching edges 10a, 11a, 12a and 13a of the section A. The sections B and C also have matching edges 14, 14a which are to be joined together.

In order to properly identify these various edges and to indicate to the seamstress how they are to be joined, the various sections A, B, etc. are marked with seam indicating lines 15, 16, 17, 18 and 19, which lines are disposed adjacent and substantially parallel to the edges to be joined and are substantially coextensive with the length of seams for joining the same. Moreover, in order to properly distinguish the edges in each pair to be joined from other edges of the garment sections, the seam indicating lines for each pair of matching edges are marked with matching indicia, such as for example, the squares 20 for the matching lines 15, the triangles 21 for the lines 16, the circles 22 for the lines 17, the diamonds 23 for the lines 18 and the "X" marks 24 for the lines 19. In addition, the lines and the indicia thereon for each pair of matching edges may be of a different color from the lines and indicia of other pairs of matching edges, it being apparent from the foregoing that in this manner the seamstress may readily identify the edges of the sections which are to be joined.

It is also contemplated that the section markings A, B, etc., provided on the sections themselves in a systematic order, whereby to indicate, by their alphabetical (or numeral) progression the sequence in which the sections are to be assembled. Such markings, as well as the seam indicating lines and indicia, are intended to be made with so-called fugitive colors, well known in the art, so that they automatically disappear after they have served their purpose.

Apart from their primary purpose of identifying the matching edges of the garment sections, the seam lines 15, 16, 17, etc., also serve to indicate to the seamstress the actual location of the seam to be sewn as well as its approximate length. The seam indicating lines and indicia are marked on the "reverse" side of the material and when the garment sections are to be joined, they are placed "back to back" as shown in Figure 2 and the seam 55 is simply sewed along the seam line visible on top when the superposed sections are placed in a sewing machine.

In order to assure that the seam indicating lines of the superposed garment sections are in proper alignment, the garment sections are provided adjacent the ends of the seam lines with punched sight apertures 25 surrounded by colored markings 26 for easy visibility. Thus, when the sections are placed back to back, the seam lines may be readily aligned by simply aligning the sight apertures, as will be clearly apparent.

It is to be also noted that the seam indicating lines and consequently, the finished seams, are accurately located with respect one to another rather than with respect to marginal edges of the garment sections. In this manner, assurance is had that the assembled garment is of the proper size and fit, which necessarily is not the case in conventional practice where the seamstress attempts to merely follow the edge of the material at constant spacing

and any variations therefrom usually produce accumulative errors and resultant ill-fitting.

In the event it is desired to temporarily hold marginal edges of two sections together, as is done by conventional basting, the invention contemplates the use of substantially U-shaped clips 27 of resilient material, which may be simply slipped over the superposed or juxtaposed marginal edge portions of the sections, as is illustrated in Figure 2. The clips 27 firmly hold the sections together, yet may be easily removed when so desired, and the use of troublesome pins for basting purposes is eliminated.

As already stated, the sections A, B, C, etc., may be pre-shaped and pre-cut into the form of individual pieces ready for assembly. On the other hand, if so desired, such pieces may be embodied in a unitary sheet or piece of material 28 as shown in Figures 3 and 4. In such event, the sections illustrated as K, L, M, N, etc., are laid out on the sheet 28 and the sheet is provided with lines of perforations 29 which coincide with the marginal edges of the respective sections. The sections may be easily separated from the sheet by simply tearing the same along the perforated lines. The seam indicating lines 15, 16, etc. and the indicia 20, 21, etc. are marked on the sections K, L, M, etc., as already explained.

The various garment sections, clips 27, thread, buttons, and all other material required for the assembly of a particular garment may be contained in a single package, appropriately marked with the style, size and color of the garment, for purposes of convenience. Also, in the event that the garment is of a complex form, the sections within the package may be separated into sub-assemblies intended for individual construction prior to their final assembly into the complete garment.

It will thus be seen that we have provided means for convenient, simple and accurate garment construction from pre-shaped garment sections with self-orienting means for assembling the same, such as may be satisfac-

torily undertaken even by persons with little or no previous sewing experience.

While in the foregoing these has been described and shown the preferred embodiment of the invention, various modifications may become apparent to those skilled in the art to which the invention relates. Accordingly, it is not desired to limit the invention to this disclosure and various modifications may be resorted to, such as may lie within the spirit and scope of the appended claim.

10 What is claimed as new is:

15 In prefabricated garment construction, the combination of a plurality of pre-shaped garment sections having pairs of matching edges adapted to be stitched together, seam indicating lines marked on said sections adjacent and substantially parallel to said edges, said lines being substantially coextensive with seams to be sewn therethrough for joining said sections together, matching indicia marked at the seam indicating lines of the matching edges in each pair for distinguishing the same from other seam indicating lines, said sections being provided adjacent the ends of said seam indicating lines with sight 20 apertures for locating one seam indicating line upon another when said sections are superposed, and colored markings provided on said sections surrounding said apertures whereby to render the same easily visible.
